UNITED STATES PATENT OFFICE.

OTTO HEINS, OF NEW YORK, N. Y., AND CHARLES M. WILD, OF SPRINGFIELD, MASSACHUSETTS, ASSIGNEES TO BOSCH MAGNETO COMPANY, OF NEW YORK, N. Y., A CORPORATION OF NEW YORK.

MAGNETO.

1,264,931.

Specification of Letters Patent.

Patented May 7, 1918.

Application filed December 27, 1915. Serial No. 68,841.

To all whom it may concern:

Be it known that we, OTTO HEINS, a subject of the Emperor of Germany, residing at New York city, county and State of New York, and CHARLES M. WILD, a subject of the Emperor of Germany, residing at Springfield, county of Hampden, State of Massachusetts, have invented certain new and useful Improvements in Magnetos; and 10 we do hereby declare the following to be a full, clear, and exact description of the invention, such as will enable others skilled in the art to which it appertains to make and use the same.

15 The customary bipolar magneto producing two ignition voltages per rotation is unsatisfactory in electric ignition systems for high-speed four-cycle internal combustion engines operating at 2500 to 3500 R. P. M., 20 and having four or six cylinders, and also for eight and twelve cylinder four-cycle engines operating at low speed. This is due to the fact that the centrifugal force acting on the deflecting interrupter element sometimes causes the magneto to miss, and also to the fact that the magneto gearing operates unsatisfactorily at the high speed.

The present invention relates to a magneto of novel form wherein a bipolar armature coöperates with a four pole field member to produce four ignition voltages per rotation, and in the preferred construction within our invention, the armature is of the ordinary shuttle form, whereas the field member is composed of two permanent magnets of horse-shoe form arranged side by side along the axis of rotation of the armature, and having poles disposed on quartered diameters embracing separate axial 35 portions of the armature. This magneto may be mounted directly on the crank shaft of an eight cylinder four-cycle engine and thereby eliminate the magneto gearing and operate at engine speed, or it may be driven 40 through appropriate speed change gearing from an engine having six, twelve, or other number of cylinders. In order that the distributing gearing also may be eliminated, the distributor for the magneto may be of 45 the type in which sparks are produced simultaneously at two spark plugs in series at each period of ignition, as will appear hereinafter, although, if desired, the distributor may be of the ordinary kind driven

from the magneto through two to one speed 55 reducing gearing.

In the accompanying drawings illustrating the preferred embodiment in application, as an example, to a magneto having direct driven distributing mechanism, 60

Figure 1 is a section of the magneto on line 1—1 of Fig. 2;

Fig. 2 is a section on line 2—2 of Fig. 1;

Fig. 3 is a section on line 3—3 of Fig. 1;

Fig. 4 is a side elevation of the magneto 65 partly broken away;

Fig. 5 is a front view of the mechanical interrupter; and

Fig. 6 is a wiring diagram.

The armature core is of the ordinary 70 shuttle type having a cross bar 1 connecting two polar projections 2, and is mounted for rotation in the bearings 3. The core is provided with a primary winding 4 and a secondary winding 5.

The field member is stationary and is composed of two permanent magnets 6 and 7 of horse-shoe form, arranged side by side along the axis of rotation of the armature, as shown. It will be observed that in each magnet one arm is shorter than the other, the short arm 6' of the magnet 6 being on the same side of the magneto as the long arm 7'', and the short arm 7' of the magnet 7 being on the other side of the magneto 85 with the long arm 6''. The magnet 6 is provided with diametrically-disposed pole shoes 8' and 8'' arranged at right angles to the diametrical line of the pole shoes 9' and 9'', both diameters lying midway between 90 the vertical and the horizontal planes containing the axis of rotation, as indicated by the broken lines in Figs. 2 and 3. It will also be observed that the magnet 6 and its pole shoes 8' and 8'' are wider measured 95 along the axis of rotation than the magnet 7 and its pole shoes 9' and 9''. The adjacent magnet arms 6' and 7'' are of one polarity, say north, while the adjacent magnet arms 6'' and 7' are of the other polarity. 100 Thus, each armature pole extending axially into coöperation with both magnets 6 and 7, encounters in each rotation two pole shoes of one polarity, and then two pole shoes of the opposite polarity.

The mechanical interrupter for periodically interrupting the circuit of the primary winding 4 comprises the grounded inter-

rupter element 10 and the insulated element 10', both mounted for rotation with the armature, and the four equally spaced interrupter cams 11 carried by a normally stationary cam ring 12 provided in the well known way with a lever 25 for adjusting at will the circumferential position of the cam ring to advance or retard the period of ignition throughout the timing range. One terminal of the primary winding 4 is connected to the insulated interrupter element 10', and the other terminal is grounded on the armature core. The coil condenser 13 is mounted fast with the armature core and is electrically connected between the insulated interrupter element 10' and the armature core, the brush 14 engaging the brass sleeve 15 around the condenser to electrically connect the armature core directly to the field frame.

The two terminals of the secondary winding are connected respectively to the distributor segments 16 and 16', which are embedded in the two insulating rings 17 and 17' at diametrically-disposed places. The distributor segments 16 and 16' are carried by the armature for rotation therewith and successively engage the two stationary series of spring-pressed brushes 18 and 18', which are individually connected to the insulated electrodes of the spark plugs.

The magneto shown may be driven directly from the crank shaft of an eight cylinder four-cycle engine. An ignition voltage is generated in the secondary winding 5 in each period that the polar projections 2 of the armature core bridge the spaces between the pole shoes of each magnet 6 and 7, the mechanical interrupter being opened at the time by reason of the engagement between a cam 11 and the deflecting interrupter element 10. Inasmuch as the pole shoes of the two magnets 6 and 7 are disposed on diametrical lines at 90 degrees to each other, each polar projection 2 will, during each rotation of the armature, first bridge a space between the pole shoes of one magnet, then a space between the pole shoes of the other magnet, then a space between the pole shoes of the first magnet at 180 degrees from the first position, and finally bridge a space between the pole shoes of the second magnet at 180 degrees from the second position, each of these positions occurring at intervals of 90 degrees around the circle. In each position in which a part of the polar projections 2 of the armature core bridge the spaces between the pole shoes of one magnet, the other part of the polar projections register with the pole shoes of the other magnet. The ignition voltage generated at that time in the armature results from the simultaneous interruption of the primary circuit at the interrupter contacts and the diversion of the magnetic flux of one mag-

net from its prior path through the polar projections 2 and the cross bar 1 of the armature to the path across the polar projections alone, the time rate of change of the magnetic flux interlinking with the primary winding 4 being sufficient to generate a satisfactory ignition voltage in the secondary winding 5. The magnetic flux from the other magnet does not materially affect the ignition voltage generated at that time because its path through the remaining part of the polar projections 2 and the cross bar 1 remains substantially unchanged. In order to prevent the passage of magnetic flux from one to the other magnet, it is preferable, though not essential, to magnetically insulate that part of the armature core which coöperates with the pole shoes of one magnet from the remaining part of the armature core which coöperates with the pole shoes of the other magnet, as, for instance, by means of the I-shaped member 19 of brass, and also to magnetically insulate the two sets of pole shoes from each other and the two magnets from each other by the member 20 of aluminum. The base 21, together with the side plate 22 and the side plate 23 carrying the distributor brush housing 24, are of non-magnetic metal, as aluminum.

The magnet 6 and its pole shoes 8' and 8'' extend from the brass member 19, which is at the center of the armature core, to substantially the outer end of the brass sleeve 15, and thus this magnet 6 and its pole shoes 8' and 8'' are wider than the magnet 7 and its pole shoes 9' and 9'', which extend along substantially one-half of the axial length of the armature core, that is, from the central brass member 19 to the other end of the core. In this way, a nice mechanical design is attained, and the four ignition voltages generated in each rotation are substantially of equal value throughout the entire timing range with the proportions herein shown between the magnets 6 and 7.

Having thus described our invention, what we claim is:

1. In a magneto for electric ignition systems, a rotatable bipolar armature with polar projections, and a four-pole field member composed of two permanent magnets, having poles embracing different axial parts of the armature, the polar projections of the armature being designed to bridge the spaces between the poles of a single one of the magnets at a time.

2. In a magneto for electric ignition systems, a rotatable bipolar armature with polar projections, and a four-pole field member composed of two permanent magnets having poles embracing different axial parts of the armature, the polar projections of the armature being designed to bridge the spaces between the poles of a single one of the magnets at intervals of 90 degrees.

3. In a magneto for electric ignition systems, a rotatable bipolar armature with polar projections, and a four-pole field member composed of two permanent magnets having poles embracing different axial parts of the armature, one axial part of the polar projections being designed to bridge the spaces between the poles of one of the magnets while the other axial part thereof 5 simultaneously registers with the poles of the other magnet.
4. In a magneto for electric ignition systems, a rotatable armature of shuttle form, and a four-pole field member composed of two permanent magnets each having poles embracing a different axial part of the armature.
5. In a magneto for electric ignition systems, a rotatable bipolar armature of shuttle form, and a four-pole field member composed of two horse-shoe magnets each having pole shoes disposed on a diameter at right angles to that of the pole shoes of the other magnet and embracing a different 10 axial part of the armature.
6. In a magneto for electric ignition systems, a rotatable armature, and a four-pole field member composed of two horse-shoe magnets arranged side by side along the armature and having poles embracing different axial parts thereof.
7. In a magneto for electric ignition systems, a rotatable armature, and a four-pole field member composed of two horse-shoe magnets arranged side by side along the armature, each magnet having poles disposed on a diameter at right angles to that of the poles of the other magnet.
8. In a magneto for electric ignition systems, a rotatable armature, and a four-pole field member composed of two horse-shoe magnets arranged side by side along the armature, each magnet having poles disposed on a diameter at right angles to that of the poles of the other magnet and intermediate of the horizontal and vertical planes containing the axis of rotation.
9. In a magneto for electric ignition systems, a rotatable armature, and a four-pole field member composed of two horse-shoe magnets arranged side by side along the armature, each magnet having a long arm and a short arm so arranged that the poles of one magnet are disposed on a diameter at right angles to the poles of the other magnet.
10. In a magneto for electric ignition systems, a rotatable armature, a condenser fast to the armature at one end thereof, and a four-pole field member composed of two horse-shoe magnets arranged side by side along the armature, said magnets being of different widths for the purpose described.
11. In a magneto for electric ignition systems, a rotatable armature having two axial parts magnetically insulated from each other; and a four-pole field member therefor composed of two permanent magnets having poles embracing the respective parts of the armature.
12. In a magneto for electric ignition systems, a rotatable armature, and a four-pole field member therefor composed of two permanent magnets having poles embracing different axial parts of the armature, the two magnets being magnetically insulated from each other.
13. In a magneto for electric ignition systems, a rotatable armature, and a four-pole field member therefor composed of two permanent magnets arranged side by side and having poles embracing different axial parts of the armature, and a spacing member of non-magnetic material arranged between the magnets to magnetically insulate them from each other.
14. In a magneto for electric ignition systems, a rotatable armature, and a four-pole field member therefor composed of permanent magnets producing two poles of one polarity followed by two poles of the opposite polarity.
15. In a magneto for electric ignition systems, a rotatable armature, and a four-pole field member therefor having permanent magnets with poles embracing different axial parts of the armature and producing two poles of one polarity followed by two poles of the opposite polarity.
16. In a magneto for electric ignition systems, a rotatable armature, and a four-pole field member therefor composed of two permanent magnets of horse-shoe form arranged side by side along the armature with magnet arms of like polarity adjacent each other.
17. In a magneto for electric ignition systems, an armature core, a four-pole field member composed of two permanent magnets each having poles embracing a different axial part of the armature core, and a generating winding mounted on the armature core in coöperation with the poles of both magnets.
18. In a magneto for electric ignition systems, an armature core, a four-pole field member composed of two permanent magnets each having poles embracing a different axial part of the armature core, and a generating winding embracing the armature core in coöperation with the poles of both magnets.
19. The combination with a magneto having a rotatable armature with primary and secondary windings, and a field member co-operative with the armature to produce four ignition voltages per rotation, of spark plug distributing segments connected to the respective terminals of the secondary winding and carried by the armature at axially separated places.

20. The combination with a magneto having a rotatable armature with primary and secondary windings, and a field member co-operative with the armature to produce four
5 ignition voltages per rotation, of distributing mechanism comprising two segments connected to the respective terminals of the secondary winding and carried by the arma-

ture at separated axial places, and eight stationary spark plug distributing brushes arranged in two circular sets co-operative with the segments. 10

In testimony whereof we affix our signatures.

OTTO HEINS.
CHARLES M. WILD.
